PIN FOR HOLDING SOFT COLLARS.

1,398,483.

Specification of Letters Patent. Patented Nov. 29, 1921.

Application filed October 18, 1920. Serial No. 417,653.

To all whom it may concern:

Be it known that I, THERON S. CURTIS, a citizen of the United States, and resident of North Attleboro, in the county of Bristol 5 and State of Massachusetts, have invented certain new and useful Improvements in Pins for Holding Soft Collars and the like, of which the following is a specification.

This invention relates to devices for holding together the edges of soft collars or other articles and is intended to provide a simple and convenient device that shall satisfactorily accomplish the purposes for which such articles are intended.

15 To make a satisfactory soft collar holder it is necessary that the edges of the collar should be held in correct position without puckering or wrinkling and that the device shall also be capable of ready adjustment to and 20 detachment from the collar or other article to be fastened. Heretofore it has been proposed to use a one piece pin with its opposite ends bent into hooks adapted to be inserted in the opposite ends of the down turned portions 25 of the opposite ends of the collar, but it is not usual to insert such pins so that they will be accurately positioned to properly hold the edges of the collar without wrinkling since the edges of the collar must be 30 drawn together from normal position to allow for inserting the reversely or inwardly bent hooks into the fabric. If the collar edges are drawn too close together when so inserting the hook there would be an undue 35 tension on the collar leading to wrinkling or puckering, whereas if the hooks are inserted too near the respective edges of the collar the device does not function properly in holding the edges in normal relation.

40 To overcome these objections I have devised a form of holder which permits the insertion of the hooks without displacing the edges of the collar from normal position while allowing the hooks to contact toward 45 each other to compensate for the difference in distance between the reversely bent points of the hooks and the distance between the curved shank portions of the hooks which engage and hold the two parts of the fabric 50 after the device has been inserted. The slight contraction caused by the tension spring also aids in causing the device to function properly as a holder without causing wrinkling.

To this end the invention comprises essentially a pair of reversely bent pointed hooks adapted to pierce the fabric which hooks are mounted so as to be extended apart for the purpose of insertion and then automatically contract toward each other to 60 properly position them for the performance of their function by means of a light spring tension. This and other features of the invention will be described in the specification and will be defined in the claims here- 65 to annexed.

In the accompanying drawings I have illustrated two forms embodying the principles of this invention in which:

Figure 1 is a longitudinal central section 70 showing the preferred form or arrangement.

Fig. 2 is a plan view thereof;

Fig. 3 is a plan view of a modified form 75 of the invention.

Fig. 4 is a side elevation partly in central section of such modified form.

In the practice of the invention according to the form illustrated in Figs. 1 and 2 of the drawings, I provide two slidable or 80 telescoping members 1 and 5 in this case each of them being of tubular construction. The outer longitudinal member 1 is of proper interior diameter to receive and permit a sliding movement of the 85 inner longitudinal member 5. Both members 1 and 5 are provided with reversely bent pointed hooks 3 and 6 respectively adapted to pierce through and hold the fabric elements to be fastened. 90

The outer member 1 is cut away on its upper side as shown at 2 to permit a lug or lip member 7 to project through the open recess at 2 in order to facilitate the extension or expansion of the device. At its inner 95 end the longitudinal member 1 is provided with a projecting lip 4 coöperating with the lip 7 thus forming on each member coöperating lugs adapted to be pinched between the thumb and finger and forming both a 100 holding means and also means for expanding or extending the device temporarily for the purpose of inserting it into the opposite portions of the fabric to be fastened.

In this case a contractile spiral spring 8 105 suitably secured to the two telescopic members acts to draw them normally together, their outward movement being limited or

stopped by the contact of the abutting edges 9 and 10. The outward extension or movement is limited by engagement of the member 7 with the outermost edge of the recess 5 2 thereby preventing the complete separation of the two members.

When it is desired to apply the device to the collar the collar is pressed smooth with one hand, the device is seized by the 10 two projecting lugs or lips 4 and 7 which are pressed lightly toward each other between the thumb and finger to lengthen or extend the device, and the hooks are then pressed through the two portions of the collar. The 15 device being then released, sufficient contraction is caused by the spring tension to draw the hooks nearer together to compensate for the difference in distance between the reversely bent points of the hooks 20 and the inside of the curved portion of the shank which forms the holding engagement with the fabric when the hook is in place. As this movement of contraction compensates for the overlap of the hooked points, 25 the device automatically adjusts itself to correct holding position without wrinkling the fabric.

In Figs. 3 and 4 there is shown a modified form of the device made up of three 30 members instead of two. The main or body member 12 forms an intermediate holding tube for connecting the two telescopic end members 14 in sliding relation with each other. At its top and bottom 35 ends the top and bottom end edges of the tubular body 12 are bent to form overlapping lips 13 of a width sufficient to project into the interior slot formed inside of each of the sliding members 14. The reversely 40 bent hooks 16 are secured to the extreme end portions of the slides 14. The interior slots formed in each slide 14 are closed, that is, they do not extend entirely to either extremity of the slide thereby leaving a 45 cross-bar 17 which serves as an abutment to receive the inner end of the coiled spring 18 and sustain the thrust thereof. The other end of the spring 18 thrusts against the projecting lip 13 of the holder 12 so that 50 each slide is normally pressed inwardly toward the other by its spring 18 which is

capable of being drawn outwardly to permit proper insertion of the points through the fabric of the collar.

With this form of the device one hook is 55 first inserted in one flap of the collar on one side of the vent and the opposite flap of the collar is then drawn over and hooked into the other point, the device then automatically adjusting itself to position to hold 60 the edges of the collar in proper relationship.

What I claim is:

1. A soft collar holder embracing in its construction a pair of telescopic longitudinal members, one arranged to slide inside the other, each being provided with an outwardly projecting lip adapted to be pinched between the fingers, a reversely bent pointed hook secured to the outer end of each member, and an interior tension spring connected to each member and acting to draw the hooks toward each other while permitting them to move farther apart when said lips are pinched together, substantially as described. 75

2. A soft collar holder embracing in its construction two longitudinal members arranged to slide longitudinally on each other, a reversely bent hook fixed to the outermost ends of the respective members, an integral 80 lip projecting from the inner ends of the respective members in opposition to each other, and a coiled spring acting normally to draw the hooks toward each other while allowing their further separation for purposes of insertion into the collar, substantially as described.

3. A holder for soft collars and the like, embracing in its construction two relatively movable hook members having reversely 90 bent hooks arranged in opposition to each other, a tension spring normally acting to draw said hooks toward each other each hook member being provided with a projecting portion adapted to be seized by the 95 fingers of the user and arranged to force the hooks apart when said projecting portions are pinched together between the fingers, substantially as described.

In witness whereof I have subscribed the 100 above specification.

HERON S. CURTIS.
